UNITED STATES PATENT OFFICE.

ADOLPH M. HOLSTEIN, OF SYRACUSE, NEW YORK.

DESIGN FOR FURNITURE, CASKET, INTERIOR, OR EXTERIOR DECORATION.

52,098.

Specification for Design.

Patented June 11, 1918.

Application filed August 22, 1917. Serial No. 187,547. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for Furniture, Casket, Interior, or Exterior Decoration, of which the following is a specification, reference being had to the accompanying drawing, forming a part hereof.

The drawing is a face view or front elevation of my design.

This design consists of the representation of a triangular arrangement of bamboo like

rods crossing each other near their ends, and interwoven with twigs, leaves and flowers entwined in serpentine fashion about the same on symmetrical lines.

I claim:

The ornamental design for furniture, casket, interior or exterior decoration, substantially as shown and described.

In testimony whereof, I have hereunto signed my name, at Syracuse, in the county of Onondaga, and State of New York, this 29th day of June, 1917.

ADOLPH M. HOLSTEIN.
